[57] CLAIM

The ornamental design for a pivoting latch for securing the lid of a container, as shown and described.

DESCRIPTION

FIG. 1 is a top, front, and left side perspective view of a pivoting latch for securing the lid of a container showing my new design;

FIG. 2 is a top, rear, and right side perspective view thereof;

FIG. 3 is a reduced front elevational view thereof;

FIG. 4 is a reduced top plan view thereof;

FIG. 5 is a reduced bottom plan view thereof;

FIG. 6 is a reduced rear elevational view thereof; and FIG. 7 is a reduced right side elevational view thereof, the left side being a mirror image of that shown.
